UNITED STATES PATENT OFFICE.

RUSSELL B. PERKINS, OF MERIDEN, CONNECTICUT, ASSIGNOR TO EDWARD MILLER & CO., OF SAME PLACE.

SHADE-HOLDER.

SPECIFICATION forming part of Letters Patent No. 339,923, dated April 13, 1886.

Application filed February 8, 1886. Serial No. 191,147. (No model.)

To all whom it may concern:

Be it known that I, RUSSELL B. PERKINS, of Meriden, in the county of New Haven and State of Connecticut, have invented a new 5 Improvement in Shade-Holders; and I do hereby declare the following, when taken in connection with the accompanying drawings and the letters of reference marked thereon, to be a full, clear, and exact description of the same, 10 and which said drawings constitute part of this specification, and represent, in—

Figure 1, a side view of the upper portion of the fount and burner with the shade-holder arranged thereon; Fig. 2, a top view of the 15 fount, the burner removed, showing the shade-ring in place, full size; Fig. 3, a perspective view of the ring detached, looking from above; Fig. 4, an under side view of the ring; Fig. 5, a section cutting across the projection 20 *d* on line *xx*; Fig. 6, a side view of the wick, showing its connection with the wick-adjusting rod.

This invention relates to an improvement 25 in the construction of shade or globe holders adapted to be removably attached to the lamp, and with special reference to the lamp commonly known in the market as the "Rochester Lamp." This lamp is of Argand character, the wick adjustment being by means of a vertical rod which extends down outside the 30 burner into the body of the lamp, and at its lower end secured to a ring which embraces and holds the lower end of the wick, and so that as the rod is raised or lowered the wick 35 is adjusted accordingly, the wick and rod moving together.

The construction referred to is seen in Fig. 1, in which A represents the lamp-fount; B, the body of the burner; C, the chimney-holding 40 springs; D, the wick-adjusting rod, which is arranged vertically outside the burner, and so as to be moved up and down in a line parallel with the vertical axis of the burner. In this method of adjustment the rod is attached to a 45 ring at its lower end, the ring being adapted to receive and engage with the lower end of the wick, as seen in Fig. 6, and so that as the rod is moved up and down the wick will be moved accordingly. In this construction of 50 burner and wick-adjusting device there is no room to apply the shade or lamp holding sup-

port inside the rod D, and if the shade-holding device be arranged upon the lamp-fount outside the rod, then access to the rod is made difficult and inconvenient.

The object of my invention is to construct 55 the support for the shade-holder so that it may embrace the body of the burner or neck of the fount into which the burner sets, and without interference with the adjusting-rod. 60 To this end my invention consists in a ring constructed to surround the body of the burner or neck of the fount, with an extension therefrom radially at one side, with an opening through said extension corresponding to the 65 said rod, and so that the ring may be set to its place around the burner and over the rod, the said ring provided with supports or arms to carry the shade or globe, as more fully hereinafter described.

The base of the holder is in the form of a 70 ring, *a*. Around its inner edge is an upwardly-projecting flange, *b*, the internal diameter of the ring and flange being such as to embrace the body of the burner or the neck or collar 75 *E* of the fount. At one point in the ring a radial projection, *d*, is formed, in which is an opening, *e*, of sufficient extent to set over the rod D and permit the free working of the rod through such opening. (See Fig. 2.) 80 Preferably this extension is made in height corresponding to the flange *b*, and so that its sides form a continuation of the flange, open from the under side, as seen in Figs. 4 and 5, and so as to form a recess, *f*, surrounding the 85 opening *e*, the said recess adapted to embrace or set over the tubular projection *F*, formed on the fount, through which the rod works.

From the ring arms *g* extend radially outward and upward, preferably three in number, 90 and terminate in a suitable shape to support the shade or globe. By this construction the base of the holder is brought close up to the body of the burner, and so as to leave the wick-adjusting rod substantially as free as if 95 the shade-holder were not present.

The tubular extension *F* necessarily opens into the space *G* around the wick-tube *H*, (see Fig. 2,) in order that the rod D and the wick it carries may be drawn entirely from the 100 fount; hence the opening *e* extends through the inside of the ring, as shown, so that the

wick-adjuster and wick, with the burner, may be removed without taking the shade-holder from its place around the neck E.

I claim—

- 5 The combination of the lamp-fount constructed with an opening outside the collar, and with an upward tubular extension, F, around said opening, the wick-adjusting rod D, arranged vertically through the said tubular extension F, the said rod carrying at its lower end a ring for attachment to the lower end of the wick, and the ring a, adapted to set around

the neck or collar of the lamp, and constructed with a radial projection, d, corresponding to the tubular extension F on the fount, and 15 with an opening upward through the said projection, through which the said rod works, the said ring provided with supports adapted to carry the shade or globe, substantially as described.

RUSSELL B. PERKINS.
